[57] CLAIM

The ornamental design for a combined fence and gate,
as shown and described.

DESCRIPTION

FIG. 1 is a perspective view of a combined fence and
gate of indeterminate length with the gate portion omitted
for convenience of illustration.

FIG. 2 is an enlarged plan view of a portion of the
fence;

FIG. 3 is a section view taken at section 3—3; and

FIG. 4 is a fragmentary front view of the combined
fence and gate with the gate portion shown.
